UNITED STATES PATENT OFFICE

LOUIS H. MORIN, OF NEW YORK, N. Y., ASSIGNOR, BY MESNE ASSIGNMENTS, TO
DOEHLER VENDING MACHINES, INC., A CORPORATION OF NEW YORK

WEB-DISPENSING DEVICE

Application filed April 27, 1928. Serial No. 273,169.

This invention is a divisional part of that disclosed and claimed in application Serial No. 238,288, filed December 7, 1927, for coin controlled mechanism, which discloses this invention as embodied in a coin controlled vending machine. This invention relates to the dispensing features as distinguished from and to the exclusion of the coin controlled features and relates more particularly to the dispensing of a folded continuous web of paper toweling. For the sake of clarity and simplicity of illustration, features of construction relating more particularly to coin controlled operation have been omitted from the drawings.

Among the objects of the invention are facility of manufacture, simplicity of construction, convenience in use, effective operation, and reliability. Another object is to provide a dispensing device of the kind above noted which is particularly adapted to be embodied in a commercial vending machine in associated operating relation with the coin controlled mechanism disclosed in the above mentioned application. Other objects and advantages will hereinafter appear.

The invention, as carried out in view of the foregoing objects, includes various features of construction and combinations of parts as will appear from the following description.

One embodiment of the invention which is illustrated in the accompanying drawings will now be described and thereafter the invention will be pointed out in claims, reference now being had to the drawings, in which:

Fig. 1 is a front elevation of a vending machine embodying the invention;

Fig. 2 is a horizontal section substantially on the zig-zag line 2—2 of Fig. 1, with parts relating to coin control omitted;

Fig. 3 is a vertical section substantially on the line 3—3 of Fig. 4, taken for the most part just back of the front plates and front door, showing parts of the delivery mechanism in front elevation, parts of the coin controlled mechanism being omitted.

Fig. 4 is a vertical section substantially on the zig-zag line 4—4 of Fig. 3;

Fig. 5 is for the most part a vertical sec-

tion taken on the zig-zag line 5—5 of Fig. 6;

Fig. 6 is a somewhat irregular vertical section substantially similar to Fig. 4 but showing some of the operating parts in side elevation and also showing the magazine of the machine as empty;

Fig. 7 (sheet 1) is an individual rear elevation of a rotatable operating gear and some of its immediately associated parts substantially as viewed from the vertical line 7—7 in Fig. 6 or as similarly viewed in Fig. 4, and

Fig. 8 is a similar enlarged view with the peripheral parts broken away to save space.

In the embodiment of the invention illustrated in the accompanying drawings and now to be particularly described, the operating mechanism of the machine is contained within a rectangular casing box which may be formed of suitable sheet metal such as steel by means of ordinary stamping and welding operations. This casing box has a bottom 1, back 2 from which the machine may be conveniently supported so as to leave its bottom clear, right and left side walls 3 and 4, a front door 5 and a cover or top door 6. The front door 5 is hinged along its right edge at 7 to the side wall 3 and the top door 6 is hinged along its rear edge at 8 to the back wall 2.

The front door 5 is cut out adjacent its left edge to expose upper and lower front plates 9 and 10 of the framework of the coin controlled mechanism (not shown), this framework also carrying operating parts of the dispensing device. The lower front plate 10 is secured by means of screws 11 from the inside to a main frame plate 12 in parallel spaced relation therewith. This main frame plate is provided with a plurality of flanges, projections and bosses for various purposes including its rearward spacing from the front plates 9 and 10. This main frame plate 12 is shown as firmly secured to the front door 5 by means of rivets 13. The upper front plate 9 at its lower edge engages behind the upper edge of the lower front plate 10 and is firmly but removably secured in place adjacent its upper end and to the main frame plate 12 by means of an inside thumb screw 100.

14. In the construction shown the coin controlled mechanism is carried by the swinging front door 5. This front door also carries a considerable number of parts of the operating mechanism of the dispensing device of the present invention, as will hereinafter more clearly appear.

The front door 5 also carries at the inside thereof a removable coin box shown as comprising a rectangular body portion 15 which is permanently closed at its front by a plate 16 secured thereto and which is provided at its left side adjacent its top and front with an opening 17 for the entrance of the coins and through which they may be emptied out when the coin box is removed. The front plate 16 projects beyond the box body 15 to form a flange which is slidably received at the front of gibs providing guideways on the door 5 so that the coin box may be removed by upward sliding movement. This coin box may be locked in place on the front door 5 by means of a key-operated lock 18 riveted to the inside of the door at the right side of the coin box and having a partially rotatable bolt or catch 19 to engage in a notch cut in the right side of the coin box, as shown in Figs. 1 and 2. This coin box lock 18 is accessible for operation only from the inner side of the opened front door 5.

The casing structure further includes a container or magazine box in the rear thereof, the rear wall of which is formed by the back wall 2 of the outer casing. This magazine box is of rectangular shape and has a bottom wall or floor 20 spaced above the outer casing bottom 1, a front wall 21 spaced rearwardly from the front door 5 and shown as provided with a large central opening, a right side wall 22 spaced inward from the right casing wall 3 and a left side wall 23 spaced inward to a somewhat greater extent from the left casing wall 4. The right and left side walls 22 and 23 have at their upper ends inturned wings 24 and 25 which form paper guides at the front of and slightly spaced from the front wall 21. Transverse bracing rods 26 and 27 are provided over which respectively the upper edge of the front wall 21 and the upper ends of the guide wings 24 and 25 are turned away from each other to form rounded edges or beads. The front wall 21 has, as shown in Figs. 2, 3 and 5, right and left lateral extensions or wing portions which, below the guide wings 24 and 25, extend outward to the respective outer casing walls 3 and 4 to which they are secured.

A paper towel web 28 is contained in the magazine in the form of a folded continuous web of which the folds extend backward and forward in the container, forming a fan-fold pack from the top of which an end portion of this web extends over and is guided by the top bead or rounded upper edge of the front wall 21, behind the guide wings 24 and 25 and

continues downward and out through an exit slot in the casing bottom 1 where it is guided at its back by a rear guide strip 29 which is curved upward at the inside to form a rounded shoulder, and is guided at the front by an upwardly and downwardly bent or curve guide strip 30 spaced from the rear guide strip 29 and which projects downwardly and rearwardly at an inclination below the casing bottom 1 where it is provided with a sharp cutting edge over which a strip of the towel web 28 of the desired length may be torn off. Instead of the paper towel web 28 being in the form of a fan-fold pack, as shown, this web might be contained in the magazine in the form of a roll carried by a suitable spindle or the like. However, with the web 28 in the folded pack form as shown, a magazine of a given size will contain a greater length thereof, so that a machine of a given capacity will be correspondingly smaller and more compact. It is obvious that this web need not necessarily be paper toweling, but might be a paper or other suitable web to be used for any purpose desired.

A visual indicator is provided for showing at any time upon inspection the size of the pack of towel web 28 contained in the magazine. This indicator comprises a follower roller 31 to rest upon the top of the pack, journaled in a carrier bracket 32 which is pivoted on the horizontally turned end of a rod forming an indicator lever arm 33 which extends through a slot in the top of the left magazine wall 23 and has a forwardly extending shaft portion journaled in rear and front supports 34 and 35 which are secured to the left casing wall 4. The forward end of this shaft portion is turned inward to form a pointer or hand 36 which may move at the front of an indicating plate 37 which extends from the front support 35. This indicator plate 37 is shown as graduated and as provided with the upper and lower legends "Full" and "Empty". The indication is visible through a window in the front door 5 which is closed by a glass plate 38 supported by a holder 39 secured to this door. The magazine bottom 20 is shown (Fig. 2) as provided with a slotted opening into which the indicator roller 31 may drop (Fig. 6) when the supply of towel web 28 is exhausted, thereby to give a more positive indication of the pointer 36 that the magazine requires replenishing. It should also be noted that the roller 31, by reason of its weight, together with that of its bracket 32 and lever 33, acts as a restraining member for the web 28, as will hereinafter more clearly appear.

Near the lower left hand corner of the front door 5 the main frame plate 12 carried thereby is provided with a keeper 40 to receive the lower end of a vertically slideable latch rod 41 which is guided through lower and upper ears 42 and 43 formed on the left

extended portion of the front magazine wall 21, and is urged upwardly to disengage the keeper 40 by a coiled thrust spring 44 interposed between the lower ear 42 and a collar 5 on the latch rod. The upper end of this latch rod is turned over horizontally to engage beneath the brace rods 26 and 27 for holding the latch rod down and may be disengaged therefrom by rotating the latch rod, whereupon its spring 44 will disengage it from the keeper 40. The front door 5 is further secured in closed condition by means of a flange along the forward edge of the top door 6 which fits down over the upper edge of this front door. The top door 6 is secured in closed condition by means of a key-operated lock 45 carried thereby to be operated from the outside of the casing and having a catch or lock bolt 46 to engage beneath a keeper lug 47 riveted to the inner side of the front door 5. Thus by unlocking the lock 45 both of the doors 5 and 6 may be opened or the top door 6 alone may be opened for replenishing the magazine through its open top.

Close above the guide strips 29 and 30 and immediately below the lower edge of the front magazine wall 21, which is shown as projecting downward below the bottom wall 20, the paper towel web 28 is firmly gripped and securely held between a pair of substantially similar front and rear soft rubber feed rollers 48 and 49 by which (under coin control, not shown) it is normally restrained against being pulled out. These rollers are respectively molded upon metal, such as brass, core tubes 50 and 51 so as to be firmly secured thereto. Substantially similar bearing ends or plugs 52 and 53, which may be formed from the same die-casting, are respectively fixed in the front and rear roller core tubes 50 and 51 at their right hand ends. Also bearing ends or plugs 54 and 55 substantially similar to each other are fixed in the left hand ends of the respective front and rear roller core tubes 50 and 51. The rear roller 49 is mounted within the machine casing body while the front roller 48 is carried by the front door 5 to swing outward therewith, thereby providing for the easy insertion of the paper towel web 28 between these rollers. It will be noted that the opposite edges of the web 28 may be conveniently passed laterally behind the opposed edges of the guide wings 24 and 25, at the same time passing between the ends of the bracing rods 27, as will be clear from Fig. 3.

The outer ends of the left hand end bearings 54 and 55 are provided respectively with similar intermeshing spur gears 56 and 57 by which the two feed rollers 48 and 49 are positively connected together for co-operating rotation, but which will unmesh when the front door 5 is opened. Also,

somewhat smaller spur gears 58 and 59 are formed on the respective end bearings 54 and 55 adjacent the ends of the respective rollers 48 and 49. Each of the end bearings 54 and 55 together with its two gears may be die-cast in one piece. The forward smaller spur gear 58 on the bearing end 54 is utilized for driving the two feed rollers but the corresponding smaller gear 59 on the end bearing 55 for the rear roller 49 is not used and is present only because, for convenience of manufacture, the same die-casting is used for forming the two end bearings 54 and 55, each together with its gears cast thereon.

A shaft 60 for the rear feed roller 49 is fixed in its end parts 53 and 55 beyond which it projects and at its reduced outer ends is journaled in slots in the forward ends of bearing blocks 61 which are slidable horizontally in guideways 62 secured to the respective side walls 3 and 4 of the casing. Each of these guide brackets 62 is provided with a coiled thrust spring 63 urging the bearing block 61 forwardly to press the rear feed roller 49 against the front feed roller 48, cotter pins 64 being provided through the front ends of the guide brackets 62 against which the shaft 60 may abut to prevent the escape of the rear feed roller 49 when the front feed roller 48 is swung away from it.

The front feed roller 48 is journaled on the inturned ends of a bracket bar 65 which is secured by rivets as shown (Fig. 1) to the front door 5. The right end of this bracket bar carries a cone-shaped pivot pin 66 which forms a bearing for the right hand bearing end 52 of this front roller. The left hand end of this bracket bar 65 has threaded through it an adjustable bearing screw 67 which forms a cone bearing for the left hand gear-carrying bearing end 54 of this front feed roller and which is provided with a lock nut 68.

The feed rollers 48 and 49 (which in the vending machine are normally locked by the coin controlled mechanism) are positively driven through the intermediary of a train of toothed gears. These intermediary or connecting gears, which are shown as five in number, are journaled on and carried by a downward extension of the main frame plate 115. The smaller spur gear 58 of the front roller 48 is engaged by an idler gear 69 which in turn is engaged by a spur gear 70 which at the left side thereof has a miter gear 71 formed thereon. A spur gear 72 similar to the spur gear 70 and having its axis at right angles thereto has similarly formed thereon a miter gear 73 which engages with the miter gear 71 at the rear side thereof. These two spur gears 70 and 72 together with their respective miter gears 71 and 73, which may be formed respectively in one piece therewith, may be substantial duplicates. The latter spur gear 72 is engaged by an intermediary or idler gear 74 located at the right thereof

as viewed from the front in Figs. 3 and 5, this spur gear 72 being behind or at the back of the intermediate gear 74 as viewed from the right side of the machine in Figs. 4 and 6 and being thus indicated by dotted lines in Fig. 4.

This train of gearing for rotating the feed rollers 48 and 49 is driven by power applied to the intermediate gear 74 to rotate the latter, by a large spur gear 75 located above the intermediary gear 74 and having intermeshing driving connection therewith. This gear 75 is the first or initial gear in the train or series of intermeshing gears including in the driving connections for the feed rollers 48 and 49, and this drive gear 75 at all times has a positive connection with these rollers, as above noted. In the complete vending machine this rotatable operating member or initial drive gear 75 is operated under coin control. Manually operable means now to be described are provided in accordance with the invention for rotating the rotatable operating member or initial drive gear 75 and for continuing its unidirectional operating rotation.

A power-transmitting connecting sleeve 76 which extends inwardly is provided with a head 77 journaled in a tubular boss 78 formed on the front of the lower front frame plate 10. In the embodiment of the invention shown, a driving member for the operating member 75 is coaxial with this sleeve 76 and is shown as a disc 79 spaced rearwardly somewhat beyond the back of the frame plate 12 and provided at its front with a hub sleeve 80 journaled in a bearing extending through the main frame plate 12 and at its rear this disc is provided with a hub boss 81. At its forward end the hub sleeve 80 is provided with a square-shouldered diametral rib which seats in a corresponding complementary diametral groove in the rear end of the hub sleeve 76, as shown in dotted lines in Fig. 4, so that thereby the driving disc 79 is positively connected to the sleeve 76 for unitary rotation therewith.

The driving head 77 of the sleeve 76 is shaped to form the cup element of a friction driving clutch of the cone type and having a cooperating cone element 82. A rotatable handle knob 83 has a reduced hub portion journaled in the reduced outer end of the bore in the front boss 78 and is positively connected to the cone element 82 to rotate the latter by means of a square-faced diametral groove in the handle knob hub in which is seated a complementary square-shouldered diametral ridge on the adjacent outer face of the clutch cone 82, as is shown in dotted lines in Fig. 4. A handle shaft 84 extends inwardly through the handle knob 83, cone clutch element 82 and loosely through the sleeve 76 and driving disc 79. This shaft has a head 85 fixed on its forward end and fitting loosely in a bore or recess 86 in the front of the

handle knob 83. As it is desirable that the handle shaft 84 shall rotate with the handle knob 83, the head 85 is provided with small wings to engage and slide in longitudinal grooves in the handle knob 83 at the outer end of its bore 86 (Figs. 1 and 4). A coiled compression spring 87 on the handle shaft 85 is interposed between its head 85 and the bottom of the enlarged bore 86 in the handle knob. This spring is adjustably maintained under suitable tension by a nut 88 on the inner end of the handle shaft 84 engaging a washer 89 which abuts against the inner end of the hub boss 81 on the driving disc 79. The spring 87 thus maintains the clutch elements 77 and 82 in frictional driving engagement. The cone clutch element 82 will slip on the cup clutch head 77 to prevent breaking any part of the mechanism, which otherwise might occur.

In the embodiment of the invention shown, the rotatable operating member or gear 75 is coaxial with and is directly mounted upon its driving member 79 (see more particularly Figs. 4, 5, 7 and 8). The operating member or drive gear 75 is circularly recessed at the back to fit around the driving disc 79 and is apertured at the front to fit around the disc sleeve 80 in the space between this disc and the bearing for its sleeve on the frame wall 12. This operating gear 75 is further supported upon the drive member 79 by means of a back plate or cover plate 90, recessed or countersunk into the back thereof and fitting around the disc hub boss 81 which extends through it. This plate 90 is firmly secured to the operating gear 75, such as by means of a pair of screw pins 91 and 92.

The circular driving disc 79 is peripherally notched to provide an abrupt driving shoulder 93 which faces in a clockwise direction (Fig. 5) and is shown as radial. A coupling pawl 94, shown as of substantially lune shape, to have in part a cylindrical surface and in part a concave arcuate surface complementary to the circular periphery of the drive disc 79 and disposed immediately adjacent thereto, to be rocked into its peripheral notch so as to be engaged by its driving shoulder 93, passes through the operating member 75 in a rather deep arcuate notch in the wall of the circular recess therein which contains the driving member 79. In the position of the operating member 75 shown in the drawings the pivotal axis of this pawl 94 is above the axis of rotation of the driving disc 79 substantially in vertical alignment therewith, and the left edge or point of this pawl which is to be engaged by the driving shoulder 93 is shown as circumferentially spaced therefrom to a considerable extent.

This coupling pawl 94 is provided at the rear end thereof with an axial stem or shaft portion 95 which is pivoted in the back plate 90 of the operating gear 75 and projects rear-

wardly beyond this plate. The projecting end portion of this stem 95 carries a coiled torsion spring 96 one end of which is seated in a diametral slot in the stem and the other end of which is extended and anchored to the operating member 75 by the plate screw 92 (Figs. 4, 6, 7, and 8). As is perhaps most clearly shown in Fig. 8, this spring constantly urges the coupling pawl 94 to rock towards its engaging position, which is clockwise as viewed from the rear in Figs. 7 and 8 and counter-clockwise as seen from the front in Fig. 5.

At its forward end the coupling pawl 94 is provided coaxially therewith with a flat circular head 97 which is countersunk into the front face of the operating member 75 down to the forward face of the driving disc 79, a portion of the operating member 75 being cut away inwardly to the drive disc sleeve 80 to provide space for the pawl head 97, the periphery of which is immediately adjacent this sleeve 80 (Figs. 4 and 5). Near its lower edge the pawl head 97 is provided with a forwardly projecting pin or stud 98 which in the disengaged position of the pawl 94 is positioned in radial line with the axes of the pawl and the driving disc 79 and is shown as directly below the pivotal axis of the pawl (Figs. 4, 5 and 7). In the complete vending machine this pawl stud 98 is utilized in effecting coin control of the pawl 94, and it may be disregarded so far as the present invention is concerned.

Because of its general shape and its manner of operation, this coupling pawl 94 considered as a whole, may be termed a drive finger. This organization of the gear-forming operating member 75, with its driving member 79 and its clutch pawl 94 both substantially housed therein, provides a very compact construction. At its rear this operating member or drive gear 75 is shown as provided with a wide projecting flange which forms a guide for the towel web 28 to prevent the possibility of this web catching upon or being torn by the adjacent end of the handle shaft 84 or that of the pawl stem 95.

A coin may be inserted through a coin slot 99 in the upper front plate 9, and when the coin is freed by the coin controlled mechanism it will drop upon the inclined floor 100 of a coin chute and slide into the coin box 15 through its opening 17. This coin chute, which is formed on the main frame plate 12, also has an upper or top wall 101 to assist in guiding the coins through the opening 17 into the coin box. Just above the magazine bottom 20 the front wall 21 of the magazine has a tongue 102 struck back therefrom which forms a recess at the front thereof at the rear of a feeler (as shown) for the paper towel web 28. The feeler relates to the coin controlled mechanism.

Upon forward or clockwise rotation of the

handle knob 83, the driving shoulder 93 of the driving disc 79 will be correspondingly moved towards the disengaged coupling pawl 94, and the pawl spring 96 becomes effective to rock the engaging end or shoulder of the pawl 94 into the path of the advancing driving shoulder 93 of the rotating driving disc 79, as this shoulder now moves forward closely adjacent to the pawl, and the operating member 75, coupled to its driving member 79, is driven forward thereby. The rotatable operating member 75, being clutched to its driving member 79, is now rotating as a unit therewith. The driving disc 79 and the gear-forming operating member 75 may now continue their rotation. Thus the operating member 75 may be rotated continuously for thereby obtaining a strip of the paper towel web 28 of any length desired.

In the complete commercial vending machine, as hereinbefore noted, the clutch pawl 94 is coin controlled, thus to be made effective or ineffective. In such case of course only a predetermined limited length of the towel web 28 can be obtained for each coin inserted, but a strip of such web of any desired length may be obtained by the successive insertion of coins. As shown in the drawings and above described, without coin control, the clutch pawl 94 is at all times effective to couple the initial driving gear 75 to its driving disc 79 for continuous operation as above noted. Thus the machine is fully operable as a dispensing device, either with or without coin control.

It will be noted that the coupling pawl 94 forms a one-way clutch, so that reverse rotation of the handle knob 83 will be idle and ineffective to produce any result. It is obvious that reverse rotation communicated to the feed rollers 48 and 49 would withdraw the end of the towel web 28 within the casing and out of engagement with these rollers, which would render the machine inoperable for delivering the web.

According to this invention the follower roller 31 which rests upon the top of the pack of the folded continuous web 28 is utilized for two purposes or has a double function. In view of the preceding description and as shown in the drawings, it will now be clear that, besides serving to operate the indicating hand 36, this roller constitutes a restraining member for the web. It presses down upon the top of the folded web pack so as to hold down the folds thereof in compact relation and puts the end portion of the web under frictional tension as it is withdrawn from the pack over the top web guide formed by the upper round beaded edge of the front wall 21 of the container, by the feed rollers 48 and 49. This prevents the upper folds of the web in the pack from rising up loosely in advance. Also it straightens out the fold kinks and avoids any objectionable looseness

105

110

115

120

125

130

in the end portion of the web which is drawn, without further restraint, over the top web guide and downward therefrom in dispensing. This prevents the clogging of the machine and the tearing of the web.

The follower roller 31 performs this function by reason of its weight supplemented by the weight of its bearing bracket 32 and carrier arm 33. It may be noted that the 10 follower roller 31 restrains that portion of the top fold of the web which is between this roller and the rear wall 2 and all of the folds below the top fold while leaving free and unrestrained that portion of the top fold which 15 is between this roller and the front wall 21. The small amount of slack resulting from this latter web portion will be immediately taken up within the container and straightened out under tension, as shown in the drawings 20 (Fig. 4).

It is obvious that various modifications may be made in the construction shown in the drawings and above particularly described, within the principle and scope of the invention as defined in the appended claims.

I claim:

1. In a dispensing device, in combination, a container for a pack of reversely folded continuous web in which the folds extend 30 backward and forward, a guide for the web extending along the front of the top of the container over which the web is drawn in dispensing, a pivot shaft extending at right angles to said web guide near the top and one 35 side of the container, a swinging arm fixed to said shaft and extending transversely over the web pack in the container, a carrier bracket pivoted on the free end of said arm on an axis parallel to said shaft, a follower 40 roller journaled on said bracket on an axis parallel with said web guide and pressing down upon the top of the folded web for holding down the folds thereof and for putting the web under tension as it is drawn over 45 said web guide, and an indicating hand carried by the forward end of said shaft and visible from the outside of the device at the front for giving a visual indication of the amount of web in the web pack.

50 2. A dispensing device for a continuous web comprising a casing including a hinged front door, a transverse guide near the top of the casing over which an end portion of a stock of web in the casing is drawn in dispensing, a rear feed roller journaled in the casing body below and parallel with said guide, and a front feed roller cooperating with the rear feed roller to draw the web downward from said guide and journaled on 55 the door to swing outward therewith so as to provide for introducing the web between the feed rollers.

60 3. A dispensing device for a continuous web comprising a casing including a hinged front door, a transverse guide near the top of

the casing over which an end portion of a stock of web in the casing may be drawn in dispensing, a rear feed roller journaled in the casing body below and parallel with said guide, a front feed roller cooperating with the rear feed roller to draw the web downward from said guide and journaled on the door to swing outward therewith so as to provide for introducing the web between the feed rollers, a yieldable spring journal mounting for the rear feed roller for pressing it against the front feed roller, intermeshing gears connecting together the front and rear feed rollers to be unmeshed when the door is opened, a rotatable handle knob at the outside of the door mounted thereon with its axis at right angles to the axes of the feed rollers, a train of gears carried by the front door at the inner side thereof including miter gears and connected to the front feed roller for rotating the latter, and a rotatable driving connection including a one-way clutch between the first gear in the train and the handle knob.

4. In a dispensing device for a continuous web, in combination, a casing including a front door, a container for the stock of web including a front wall spaced rearward from the front door and over the upper edge of which the web is drawn in dispensing, and a guide wall for the web spaced rearward from the front door and at the front of the upper portion of the front wall and slightly spaced therefrom in parallel relation therewith and between the rear face of which and the front face of the front wall the outer end portion of the web is guided and may pass freely downward in dispensing.

5. In a dispensing device for a continuous web, in combination, a container for a stock of the web including a front wall over the upper edge of which an end portion of the web is drawn in dispensing, and guide wings carried by the container connected thereto on opposite sides thereof and extending inward at the front face of the side margins of the front wall in parallel spaced relation thereto and substantially coterminous at their upper ends with the upper edge of the front wall and forming unrestraining marginal guides for the end portion of the web at the margins and edges thereof.

6. A dispensing device for a continuous web comprising an outer rectangular casing body having a bottom and a back wall and side walls, a front door hinged to the forward edge of one of the side walls, a top cover door hinged to the upper edge of the back wall, a rectangular container built into the casing including a floor wall extending forward from the back wall of the casing in spaced relation above the bottom of the casing and side walls spaced inward from the side walls of the casing and a front wall spaced rearwardly from the front door and

over the upper edge of which the web is drawn downwardly in dispensing the web from a reversely folded pack thereof in which the folds extend forward and backward within the container, lateral extensions on the lower portions of the front wall of the container secured to the side walls of the casing, and guide wings for the edges and marginal portions of the web turned over inwardly from the upper portions of the side walls of the container at the front thereof in parallel spaced guiding relation with the front face of the upper portion of the front wall of the container at the side margins thereof.

7. The invention defined in claim 6, in which an exit slot is provided in the bottom of the casing substantially in line with the front wall of the container, in combination with a guide strip for the web at the rear of said slot projecting upwardly within the casing, and a front guide strip for the web spaced from the rear guide strip projecting downwardly and rearwardly below the bottom of the casing and terminating in a tearing edge for severing the dispensed web.

8. The invention defined in claim 6, in combination with a rear feed roller journaled in the casing body below the forward portion of the floor of the container with its forward face substantially in line with the front wall of the container, a front feed roller to cooperate with the rear feed roller for drawing the web downward in dispensing it and journaled on the front door to swing outward therewith to provide for introducing the web between the feed rollers, a rotatable handle knob at the outside of the front door mounted thereon with its axis at right angles to the axes of the feed rollers, and rotatable operating connections between the handle knob and the front feed roller including intermeshing toothed gears.

9. A dispensing device for a continuous web comprising a casing body having bottom and back and side walls, a hinged cover door, a front door hinged at one of its side edges, a transverse web guide spaced rearwardly from the front door near the top of the casing over which an end portion of a stock of web in the casing may be drawn in dispensing, an exit slot for the dispensed web being provided in the casing bottom, a rear feed roller journaled in the casing body in the lower portion thereof rearward from said slot, a front feed roller to cooperate with the rear feed roller for drawing the web downward from said guide in dispensing and journaled on the front door to swing outward therewith to provide for introducing the web between the feed rollers, a rotatable handle knob at the outside of the front door mounted thereon with its axis at right angles to the axes of the feed rollers, and rotatable operating connections between the handle knob and the

front feed roller including intermeshing toothed gears.

10. The invention defined in claim 9, in combination with a container within the casing for a pack of reversely folded continuous web in which the folds extend backward and forward and from which the web may be drawn over said web guide in dispensing, a restraining member for the web comprising a follower free for vertical movement in the container arranged to press down upon the top of the folded web pack for holding down the folds thereof and for putting the web under tension as it is withdrawn from the pack over said web guide by the feed rollers, and a visual indicator visible from the outside of the casing connected to the web-restraining follower to be moved thereby for giving a visual indication of the amount of web in the container.

11. The invention defined in claim 9, in combination with a container within the casing for a pack of reversely folded continuous web in which the folds extend backward and forward and from which the web is withdrawn over said web guide by the feed rollers, a pivot shaft journaled in the casing near the top and one side thereof on an axis at right angles to the feed rollers, a swinging arm fixed to said shaft and extending transversely over the web packing in the container, a carrier bracket pivoted on the free end of said arm on an axis parallel to said shaft, a follower roller journaled on said bracket on an axis parallel with the axes of the feed rollers and pressing down upon the top of the folded web pack for holding down the folds thereof and for putting the web under tension as it is withdrawn by the feed rollers over said web guide, and an indicating hand carried by the forward end of said shaft visible from the outside of the front of the casing for giving a visual indication of the amount of web in the container.

In witness whereof, I hereunto subscribe my signature.

LOUIS H. MORIN.
